METAL WORKING MECHANISM

Ernest J. Svenson, Rockford, Ill.

Application April 30, 1956, Serial No. 581,557

6 Claims. (Cl. 77—33.5)

This invention relates to a metal cutting mechanism or machine. More specifically, the invention pertains to an automatic metal cutting machine for drilling deep or long holes by step drilling. The latter term refers to metal drilling in which a rotating drill is caused to penetrate a workpiece to a predetermined depth constituting a fraction of the desired hole and then withdrawn completely from the workpiece for cleaning of chips by a flowing coolant, this cycle of steps being repeated automatically until the hole is completed.

When the relative length or depth of a drilled hole is almost ten to thirty times (or more) greater than the diameter of the hole, drilling must be done by the step drilling method, rather than by continuous drilling, to provide for removal of the chips which otherwise would choke up the drill and cause it to break.

In drilling metal workpieces, the drill is not subjected to constant resistance. The drill will be worn as drilling progresses, with resultant increased resistance to its rotation and to forward feeding thereof. The drill flutes may be partially packed with chips. Expansion due to heating of the drill may cause added resistance to the rotation of the drill. The resistance of the workpiece material may be subject to local variations.

These variations in resistance against drill movements could possibly be compensated for by providing sufficient motive power to overcome the greatest resistance to be overcome and by providing sufficient structural strength in the drill and the drill moving and supporting elements to insure against breakage when overcoming the resistance against drill movement, if, and only if, there is sufficient space available to accommodate drill moving and supporting elements having the dimensions required for such structural strength. In other words, it might be possible to provide against overloads by increasing the dimensions and thereby the structural strength of drill moving and supporting elements when there are no space limitations prohibiting such large dimensions.

In many instances, as when six or eight oil holes are to be drilled simultaneously in an automobile crank shaft, the available space does not permit the use of a drill supporting and moving structure heavy enough to resist the overloads to which it will be subjected. Hence, it has heretofore been customary to make the drill itself rather light, so that it will break under an overload rather than the drill supporting or moving element, with resultant frequent breakage of the drill. Attempts have also been made to provide other protective means against overloads, but also with unsatisfactory results, for reasons explained hereinbelow.

In drilling a plurality of holes simultaneously in a single workpiece, such as an automobile crank shaft, it has been customary to actuate a plurality of drilling units from a single source of pressurized hydraulic fluid. At any given movement, one or more such units may be removing metal, others may be withdrawn from the workpiece for cleaning and cooling, and still others may be approaching the workpiece for resumption of metal removal

2

after cleaning and cooling. Obviously, under these conditions, no protection of individual drill units against overload can be had by regulating the above noted single source of pressurized hydraulic fluid. Recourse has therefore been had to various mechanical devices associated with an individual drilling unit, but so far such mechanical devices, although operative to some extent, have not provided a completely satisfactory solution to the problem in question, although this problem has been recognized by the automobile industry for more than twenty years.

It should be explained, in this connection, that the drills in question are conventionally rotated by mechanical means (which may be provided separately for each individual drilling unit) but displaced longitudinally (for rapid traverse to, feeding into or withdrawal from the workpiece) by a fluid motor actuated by pressurized hydraulic fluid. Thus, two sources of power, and/or two power transmitting mechanisms must be controlled simultaneously and in proper relation to each other, if protection against overloads is to be effected.

It is therefore an object of the present invention to provide a metal working machine for step drilling of relatively light construction and occupying a relatively small space so that a plurality of such machines can be used for simultaneously drilling holes in a single work piece, this metal working machine being automatic in operation and, in spite of its light construction, not subject to breakage of either the drill or drill supporting or moving elements.

Another object of this invention is to provide a metal working machine of the type indicated comprising means for protecting the machine against overloads which control both a mechanical power transmitting mechanism for rotating the drill and a hydraulic device for advancing and withdrawing the drill.

A specific object of the present invention is to provide a metal working machine of the type indicated including a pump driven by the drill spindle so connected to a fluid motor for advancing the drill that the hydraulic pressure for advancing the drill upon feeding movement of the drill will be furnished by said pump whereby the feed rate of the drill per unit of drill rotation will remain constant. In other words, if drill rotation is slowed up, as when the drill becomes worn or packed with chips, or when the material of the work piece offers increased local resistance, the rate of drill advancement will be reduced correspondingly.

Another specific object of the present invention is to provide a metal working machine of the type indicated including a hydraulic system such as described in the preceding paragraph together with means responsive to drill displacement for segregating a part of said hydraulic system including the pump to form a single closed circuit upon advancement of the drill to feeding position.

Another specific object of the present invention is to provide a metal working machine of the type indicated including protective devices responsive both to torque overloads and to thrust overloads and operative to withdraw the drill from the work piece whenever overloads are encountered.

Other and further objects and features of this invention will become apparent from the following disclosure and appended claims as illustrated by the accompanying drawings wherein the same numerals indicate identical parts, and in which:

Figure 1 is a side elevational view of a drilling machine according to the present invention, with parts broken away;

Figure 30 is an enlarged cross sectional view taken along the line 30—30 of Figure 27;

GENERAL DESCRIPTION

Referring now to Figs. 1 and 2, a machine generally indicated at 10 includes a base 12 slidably supporting, on a longitudinal dovetail guide way 14, a drill head carrier 16 having a depending guide 18 received in the guide way 14. A gib 20 may be provided between the walls of the guide way 14 and the guide 18. A generally tubular ram drill head 22 is slidably supported on a horizontal bead 24 on the carrier 16 which bed is recessed lengthwise to define a dovetail guide way 26 receiving a guide 28 depending from the drill head 22. Another gib 30 may be provided between the walls of the guide way 26 and the guide 28.

A drill spindle 32 is rotatably supported (see Fig. 5) within the ram drill head 22 by front and rear ball bearings 34 and 36 and is also provided with appropriate means, such as a socket 38, for attaching a tool, for instance, a drill 40, at its projecting end. The outer race of the front bearing 34 is locked to the drill head 22 by being clamped between an internal radial drill head shoulder 42 and a nut 44 engaging screw threads in the front end of the drill head 22. The inner race is clamped between a radial shoulder 46 defined in the drill spindle 32 by the socket 38 and a nut 48 engaging screw threads on the spindle 32. Thus, the front bearing 34 carries the thrust when the ram drill head 22 is moved forwardly in a drilling operation while permitting the spindle 32 to rotate. The outer race of the rear bearing 36 is clamped against a second internal radial shoulder 50 at the rear of the drill head 22 by means of a retainer 52 engaging internal screw threads in the rear of the drill head 22. The rear bearing 36 carries a portion of any radial load which might be applied to the spindle 32 and insures that the rotation of the spindle 32 will always take place about its axis.

Referring now to Fig. 1, the spindle 32 is driven by force transmitted from a prime mover, such as an electric motor 54 adjustably mounted on a bracket 56 extending from the drill head carrier 16 and enclosed within a housing or cover 58. The shaft of the motor 54 carries a sheave 60 driving another sheave 62 through belts 64. As best shown in Fig. 4, the sheave 62 is rotatably mounted on a sleeve 66 which extends around the rear portion of the spindle 32, as by means of a ball bearing having an outer race 68 and an inner race 70. The outer race 68 is received within an internal recess in the sheave 62 and abuts against an internal radial shoulder 72 formed at the rear of the said recess in the sheave 62, while the inner race 70 abuts against a collar 74 defined on the sleeve 66, being held against this collar by a nut 76 engaging screw threads on the sleeve 66. The sleeve 66 is rotatable with, but slidably lengthwise of the spindle 32, the sleeve 66 and the spindle 32 being connected by means of splines 78 on the spindle 32 and keys 79 on the inside of the sleeve 66. A driving connection between the sheave 62 and the sleeve 66 is provided by a torque responsive safety overload clutch including parts described as follows, reference being made to Figs. 4 and 6. A plurality of cam surfaces 80 are formed on the radial face of a restricted portion 82 of the sheave 62 extending rearwardly therefrom. A generally tubular member or sleeve 84 axially slidably on the sleeve 66 but held for rotation therewith by a key 86 carries a plurality of radially extending shafts 88 equal in number to the cam surface 80. On each of these shafts there is mounted a bearing 90 which carries a roller or cam follower 92. Contact between the surfaces 80 and the cam followers 92 is maintained by a spring 94 compressed between the tubular member or sleeve 84 and a collar 96 screwed onto the rear of the sleeve 66.

The above disclosed torque responsive overload release clutch functions as follows. As the sheave 62 is driven from the motor 54, the cam faces 80 are in en-

gagement with the cam followers 92. The force transmitted from the cam faces 80 causes the followers 92 to move circumferentially, transferring this rotative motion to the sleeve 84 which, through the action of the key 86, causes the sleeve 66 to rotate and thereby also the spindle 32 connected to the sleeve 66 by the splines 78 and keys 79.

If the drill 40 or other tool carried by the spindle 32 encounters opposition to its rotation by reason of the tool being dull or being clogged or being expanded by heat generated on drilling or due to variations in the material being worked, then a portion of the force transmitted between the cam faces 80 and the cam followers 92 will be resolved along lines parallel to the axis of spindle rotation causing the sleeve 84 to move axially against the force of the spring 94. When the sleeve 84 has moved axially sufficiently far, a collar 98 thereon contacts the actuating member 100 of an electrical switch 102 which, as described hereinbelow, on actuation will cause return of the ram drill head 22 and withdrawal of the tool from the work. Thus, breakage of the tool on excessive resistance to driving torque is avoided. Note that the force of the spring 94 can be varied to provide for withdrawals at various driving torques depending on the strength of the particular tool being used and on the nature of the work being drilled.

Axial movement of the drill head 22 is effected by means of a fluid motor indicated generally at 103 and shown in Figs. 5, 8 and 9 as including a cylinder body 104 mounted in the drill head carrier 16 below the bed 24. The cylinder body 104 is formed with an internal bore 106 receiving a piston 108 which carries on its circumference a number of sealing rings 110 serving to prevent leakage of hydraulic fluid past the piston. Further, the piston 108 is fixedly attached to a rod 112 by being locked between a radial shoulder 114 formed near one end of the rod and a nut 116 threaded onto said end of the rod 112. The rear end of the cylinder body 104 is completely closed by an end cap 118 and a sealing ring 120 associated therewith. The piston rod 112 projects out of the cylinder body at the other end thereof, which other end is sealed by a cap 122, a sealing ring 124 being disposed between the cap 122 and the cylinder body 104 and a packing member 126 being disposed between the cap 122 and the piston rod 112. The sealing action of the packing 124 may be adjusted by an externally threaded nut 128 engaging internal threads in the cap 122. The projecting end of the piston rod 112 is fixedly attached to a bracket or projection 130 depending from the drill head 22 which projection may be locked between a radial shoulder 132 near the projecting end of the rod 112 and a nut 134 threaded on this end of the said rod.

The cylinder body 106 is provided, near its ends, with ports connected to conduits 136 and 138 for the flow of hydraulic fluid into and out of the bore 106, which fluid, acting on the piston 108 connected to the drill head 22 through the piston rod 112 and the projection 130, causes the drill head 22 to be displaced axially relative to the drill head carrier 16 in which the cylinder body 104 is fixed. Note that on such displacement the spindle 32 is displaced axially along with the ram drill head 22, while the sleeve 66 remains stationary.

Pump structure

The hydraulic fluid actuating the piston 108 and thereby displacing the drill head 22 on drill feeding movement thereof is caused to flow by a double piston variable pump generally indicated at 140 and driven by the drill spindle 32, as described hereinbelow with special reference to Figs. 4, 10, 11, 12 and 13. As will be disclosed in greater detail hereinbelow, the hydraulic fluid effecting drill head displacement on rapid approach and on return movement thereof bypasses the pump 140.

As best shown in Fig. 4 the sleeve 66 around the drill 75

spindle 32 is supported in front of the sheave 62 by a pair of ball bearings 142 and 144 disposed within an aperture in a column 146 projecting upwardly from the drill head carrier 16. The inner race of the bearing 142 abuts against the collar 74 on the sleeve 66 while the inner race of the bearing 144 is held in place by a split ring 148 inserted in a circumferential groove in the sleeve 66. The outer race of the bearing 142 abuts against a retainer 150 attached to the column 146 by screws 152. The outer race of the bearing 144 abuts against the radial face of a circular flange 153 projecting from the rear of a hollow pump housing 154 attached to the column 146, as by pins 155. The spaces between the outer and inner races of the bearings 142 and 144 are sealed by annular members 156.

In front of the ring 148 the sleeve 66 is restricted eccentrically as shown in Figs. 4 and 10 to define an actuating cam 158 for the pump 140. An anti-friction bearing unit including rollers 160 and an outer race 162 is mounted over this eccentrically restricted portion of the sleeve 66. The rear of the race 162 abuts the radial shoulder defined by said eccentric restriction. The sleeve 66 terminates within the pump housing 140, the terminal portion being restricted concentrically past the said eccentric restriction and having a collar 164 near its end formed with an axial flange 166. Rings 168 and 170 extend around the concentrically constricted portion of the sleeve 66 spaced by an intermediate split ring 172 fitting into a circumferential groove in the sleeve 66. The rings 168 and 170 abut respectively against the front of the race 162 and the free end of the flange 166 and thereby hold the race 162 against displacement.

The pump housing 140 is formed at its forward end with an inturned radial flange having a terminal surface 174 connected to the collar 164 by an oil seal structure including an annulus 176 having one peripheral end surface contacting the housing surface 174 with the end of the annulus abutting against a split ring 178 seated in a circumferential groove in the surface 174. At its other end the annulus 176 is offset radially inwardly at the inner end of the surface 174 to overlie the end of the sleeve collar 164 and the free end of the annulus projecting within the pump housing 140 is deflected inwardly to overlie the inside of the sleeve flange 166. A ring 180 of L-shaped cross section has a first leg 180 contacting the inside of the annulus 176, and a second leg 182 projecting radially inwardly and abutting the split ring 178. Another ring 184 has one end seated on the inside of the annulus 176 clamped between the deflected shoulder of this annulus and the end of the said first leg 180 of the L-shaped ring, the ring 184 being offset slightly toward the second or projecting leg 182 of the L-shaped ring. A coil spring 186 is disposed between the projecting leg 182 of the L-shaped ring and the ring 184, the spring pressure being transmitted by the ring 184 to an annular packing member 188 extending around the end of the sleeve 66 between the sleeve collar 166 and the ring 184.

The operating parts of the pump 140 are described as follows, again with reference to Figs. 4, 10, 11, 12 and 13. An inlet channel 190 for hydraulic fluid delivered under pressure from a conduit 192 extends transversely through the pump housing 154 below the hollow interior thereof, and this channel 190 terminates blind short of the opposite side of the housing 154. Two parallel vertical channels 194 and 196 afford communication between the channel 190 and two vertically disposed check valves indicated generally at 198 and 200. The valve 198 includes a valve chamber 202, a valve seat member 204 in said chamber, a ball valve 206 and a spring 208 backed up by a plug 210 for resiliently urging the ball against the valve seat. The valve 200 is of identical construction and is, therefore, not described in detail. Horizontal passageways 212 and 214 lead, respectively, from the valves 198 and 200 to horizontal pumping

chambers 216 and 218 containing pistons 220 and 222. A pair of vertical passageways 224 and 226 discharge fluid from the pumping chambers 216 and 218 to a pair of check valves indicated generally at 228 and 230 which are of the same construction as the valve 198. Each of the check valves 228 and 230 communicates with an outlet channel 232 discharging into a conduit 234.

In the pump 140 the pistons 220 and 222 within the pumping chambers 216 and 218 are actuated by means disposed within the hollow interior of the pump housing 154 and described as follows. A pair of bell cranks 236 and 238 are pivotally mounted on the housing at 240 and 242 and have end portions 244 and 246 for engaging respectively the pistons 220 and 222. The eccentric cam 158 of the sleeve 66 with its bearings 160 and 162 extends between the ends 244 and 246 of the bell cranks 236 and 238 for actuating the latter alternatively as the drill spindle 32 is rotated.

In the operation of the pump 140, hydraulic fluid under pressure enters from the pipe 192, flows through the passageways 190, 194 and 196, forces the check valves 198 and 200 open and enters the pumping chambers 216 and 218. Since the pistons 220 and 222 are actuated alternately by the eccentric cam 158 and its bearings 160 and 162, the fluid enters the pumping chambers 216 and 218 alternately. Thus, on clockwise rotation of the spindle 32 from the position shown in Fig. 10, the charging fluid will pass through the check valve 198 and thence into the pumping chamber 216 during the time that the piston 222 is moving outwardly during its pumping stroke. The fluid entering the chamber 216 not only fills the chamber for the next pumping stroke of the piston 220 but also serves to force the piston toward its innermost position. The fluid pumped by the piston 222 flows from the pumping chamber 218 through the passageway 226, forces the check valve 230 open and is discharged through the passageway 232 into the pipe 234. Similarly, the fluid flows from the pumping chamber 216 through the passageway 224, forces the check valve 228 open and is discharged through the passageway 232 into the pipe 234, while at the same time the other pumping chamber 218 is being filled and the other piston 220 is being forced to its innermost position by the entering fluid.

The bell crank end portions 244 and 246 which contact the eccentric bearings 160 and 162 and the pistons 220 and 222 are formed to modify the motion imparted to the pistons 220 and 222 in such a manner that the discharge fluid is delivered from the channel 232 at a uniform rate which is substantially free from pulsations.

Variations in the rate of discharge of the pump 140 is provided for by means of a shaft 248 received in a suitable bore formed in the pump housing 154 and having an end portion which serves to limit the pivotal movement of the bell cranks 236 and 238 during the charging stroke of the pistons 220 and 222. The position of the end of the shaft 248 with respect to the bell cranks can be adjusted by turning the shaft 248 which is externally threaded near its upper end and engages internal threads at the upper end of the shaft bore. If desired, a sealing ring 250 may be provided in a circumferential groove 252 in the shaft 248.

The fluid delivered by the pump 140 passes through conduits and valves (described hereinbelow) into the bore 106 of the fluid motor 103 which displaces the ram drill head 22. Since the drill spindle 32 drives the pump 140 during the feeding movement of the ram drill head 22, any reduction in the rate of rotation of the drill spindle, as when resistance to drill penetration occurs (due to variation in material being drilled, or due to the drill becoming dulled, clogged with chips or expanded by heating) will cause a corresponding reduction in the rate of fluid delivery by the pump 140 to the fluid motor and in the rate of advancement of

the ram drill head 22, with consequent reduction or elimination of drill breakage.

Control devices

The next following paragraphs will describe, first, and in part only, two control valves forming part of the hydraulic system, and, secondly, a system of dogs, switches, solenoids, levers and links serving in cooperation with the above noted two valves to control the movement of the ram drill head 22.

A main control valve indicated generally at 254 extends lengthwise, within the hollow drill head carrier 16, as shown in Figs. 3, 7, 8, 9, 19, 20, 22, 23, 24, and 25. The valve 254 includes a stem 256 slidable in two opposed aligned horizontal bores 258 and 260 formed, respectively, in two spaced housings 262 and 264 attached to the inside of the drill head carrier 16 and separated by a vertically extending space 266 spanned by an intermediate portion of the valve stem 256. As shown in Figs. 22 to 25, the valve stem portion slidable in the bore 258 of the housing 262 is formed with four transverse detent grooves 268 adapted to be engaged by a ball 270 under the urging of a spring 272 seated in a suitable bore formed in the housing 262. As also shown in Figs. 22 to 25, the detent 270 serves to retain the valve stem 256 in any one of the four operative positions of the valve 254, namely, rapid approach (valve stem at extreme right, as shown in Fig. 23), feed (valve stem at central right, as shown in Fig. 24), neutral (valve stem at central left, as shown in Fig. 22), and rapid return (valve stem at extreme left, as shown in Fig. 25).

For moving the stem 256 of the valve 254 between its four operative positions the following mechanism is provided. A shaft 276 extends horizontally through an appropriate aperture in the wall of the hollow drill head carrier 16, being journaled in a bearing 278 attached to the outside of the drill head carrier. A control lever 280 is attached to the outside end of the shaft 276 (for manual control) and also carries a projection 282 adapted to be contacted by a dog (described hereinbelow). Another lever 284 has its upper end attached to the inside end of the shaft 276 and carries at its lower end a pin 286 rotatably fitting a vertical groove 288 formed in the intermediate portion of the valve stem 256 spanning the space 266. Further, the inner half of the shaft 276 is restricted, and between the radial shoulder defined by this restriction and the lever 284 another lever 290 is pivotally arranged on the shaft 276 by means of a sleeve 292. The upper end of this sleeve 292 carries an arcuate gear rack 294 which meshes with a plane gear rack 296 slidable in a horizontal slot 298 formed in the drill head carrier 16. Lengthwise displacement of this rack 296 will swing the lever 290 about its pivot and thereby (as disclosed in detail hereinbelow) move the lever 284 and the valve stem 256 from one to another of its operative positions.

For effecting such displacement, the rack 296 carries an upstanding finger 300 adapted to be contacted by a dog (described hereinbelow) and a solenoid operated mechanism is also provided, described as follows. As shown in Figs. 3, 8, 9, 19 and 20, the drill head carrier 16 has attached to one side thereof aligned opposed solenoids 302 and 304, each operatively connected to the lower outwardly offset end of a lever 306 fulcrumed on the drill head carrier 16 at 308. The short upper arm of this lever 306 is slotted, and a pin 310 projecting horizontally from the rack 296 fits in this slot so that movement of the lever 306 under the influence of either of the solenoids 302 or 304 will be translated into horizontal displacement of the rack 296. Specifically, the solenoid 302 serves to initiate forward movement of the drill head 22 and the solenoid 304 to initiate return movement of the drill head 22, as will be described in greater detail hereinbelow. Further, the switch 102 described hereinabove controls actuation of the return

solenoid 304 along with another switch 312 actuated by a safety overload valve 314 (described in detail hereinbelow) which is responsive to high hydraulic fluid pressure on feeding of the drill head 22 against excessive resistance.

The means whereby swinging of the lever 290 moves the lever 284 is described as follows, with reference to Figs. 19, 20 and 21. Opposed aligned actuators 316 and 318 project from bores 320 and 322 formed in the housings 262 and 264 into the space 266 and contact the lever 284 for shifting the latter. These actuators are hydraulically operated by pressurized fluid flowing into and out of the bores 320 and 322 through conduits 324 and 326 from bores 328 and 330 under the control of pilot stems 332 and 334 shiftable in the latter bores by the action of the lever 290 which is contacted by the ends of the pilot stems projecting into the space 266 under the urging of springs 336 and 338 seated in the bores 328 and 330. Fluid under pressure is admitted into the latter bores through conduits 340 and 342, while passageways 344 and 346 are provided for drainage. The pilot stems 332 and 334 have restricted middle portions, so that they can be shifted between a first position (with the springs 336 or 338 compressed) where pressurized fluid can flow across such a constricted pilot stem portion from the conduit 340 or 342 into the conduit 324 or 326 and a second position (with the springs 336 or 338 expanded) where fluid can drain from the conduit 324 or 326 across such a constricted pilot stem position into the conduit 344 or 346. Thus, when the rack 296 is displaced and the lever 290 is caused to swing, the latter depresses one of the pilot stems 332 or 334, pressurized fluid is admitted into one of the bores 320 or 322 to move one of the actuators 316 and 318, and one of these actuators swings the lever 284 to displace the valve stem 256 of the control valve 254.

As disclosed hereinabove, the ram drill head 22 can be displaced at rapid approach rate, at feed rate and at a rapid return rate. The mechanical devices for controlling these rates and directions of movements are described as follows, reference being made to Figs. 2, 3, 7, 8, 9 and 19. The ram drill head 22 includes a lateral extension 348 sliding on the bed 24 and formed with a longitudinal upwardly open slot 350 having a cross-sectional configuration of inverted T-shape. A reset dog 352 is adjustably clamped to the drill head extension 348 by a screw 354 having a head disposed in the bottom of the slot 350. A pin 356 projects laterally from a bore 358 in the reset dog 352 under the urging of a spring 360 seated in said bore. A latch dog 362 is adjustably clamped to the drill head extension 248 by a screw 364 having a head disposed in the bottom of the slot 350. An arm 366 extends in a diagonal slot 368 formed on top of the dog 362, having one end pivoted around a bolt 370 and the other end projecting laterally from the dog 362 under the urging of a spring 372 seated in a bore 374 formed in said arm and receiving a pin 376 projecting therefrom into contact with the wall of the slot 368.

At the ends of the lateral drill head extension 348 laterally projecting brackets 380 and 382 are attached thereto by means of bolts 384 and 385 having heads disposed in the bottom of the slot 350. These brackets have depending end portions carrying a slip rod 386 of square cross-sectional form. A slip dog 388 is slidably threaded over the slip rod 386. Specifically, the slip dog 388 is formed with an internal vertical bore 390 in which is seated a spring 392 urging a shoe 394 against the rod 386. Further, the slip dog 388 is formed with a depending tongue 396 providing a cam surface 398. Note that the slip rod 386 carrying the slip dog 388 moves with the ram drill head 22.

A first of rear upstanding bracket 400 extending from the drill head carrier 16 and a second or front upstanding bracket 402 also extending from the drill head

carrier provide journals for the round end portions of a rock shaft 404 which is of square cross-sectional form between the said brackets and also has a feed set dog 406 threaded over its square portion. The position of the feed set dog 406 is adjustably fixed on the rock shaft 404 by means of a screw 408. The shaft 404 may be rocked by means described as follows. A pinion 410 mounted on the square portion of the shaft 404 meshes with a rack 412 slidably disposed in an appropriate bore 414 extending transversely through the bracket 402 above the shaft 404. An upstanding pin 416 on the rack 412 extends through a slot 418 communicating with the bore 414 and permitting displacement therein of the pin 416. For effecting displacement of said pin, and thereby also of the rack 412, a lever 420 is fulcrumed on top of a vertical projection 422 from the bracket 402. The lever has one end slotted at 424, and the pin 416 extends through an aperture in a block 425 slidably disposed in said slot 424 for displacement on movement of the lever 420. The other end of the latter lever is formed with a projection 426. Thus, when the arm 366 of the latch dog 362 or the pin 356 of the reset dog 352 contacts the projection 426 of the lever 420, the latter will be pivoted, the pin 416 and thereby also the rack 412 will be displaced, and the pinion 410 and thereby also the shaft 404 will be rocked.

Other means for rocking the shaft 404 are also provided. Thus, in front of the bracket 402, the shaft 404 carries a sleeve 428 provided with a control handle 430, whereby the shaft 404 may be rocked manually.

At its end the sleeve 428 in the rock shaft 404 carries an inturned arm 432 provided at its end with a transverse bore receiving a pin 434 having a head at each end. A spring 436 between the arm 432 and the forward head of the pin 434 serves to bias the pin 434 into the position shown in Fig. 7.

The shaft 404 is rockable between a first position illustrated in Figs. 3, 7 and 10 wherein the feed set dog 406 extends vertically and the pin 434 is aligned with another pin 442 described hereinbelow, and a second position wherein the lower end of the feed set dog 406 extends inwardly and the pin 434 is brought out of alignment with the pin 442. To hold the rock shaft 404 yieldably in either one of these two positions, a detent pin 438 received in a suitable vertical bore in the bracket 402 engages either of two grooves or recesses formed in the stem 428 under the influence of a spring 440 seated in said bore, as shown in Fig. 3.

The above noted bolt or pin 442 extends through a threaded bore in a forward and downward extension 444 of the bracket 380 and may be adjusted lengthwise therein by turning.

Function of control devices

The function of the above described mechanisms for controlling the movement of the ram drill head 22 is described as follows. At the start of a drilling operation, the valve 254 is in neutral position, with the valve stem in its left central position. The rock shaft 404 is in the position assumed in the last step of the preceding drilling operation, i.e., the pin 434 is out of alignment with the pin 442 and the feed set dog 406 has its lower end inclined inwardly. Further, at the end of the last previous drilling operation, the slip dog 388 has been pushed all the way back to the right. Before drilling is initiated, the positions of the reset dog 352 and the slip dog 388 are adjusted as described hereinbelow. The drilling operation is initiated either by manual operation of the control lever 280 or by actuation of a suitable switch to energize the forward solenoid 302. In either case, the lever 284 moves the valve stem 256 to its rapid approach position, i.e., to its extreme right position. It will be recalled that the control lever 280 rotates the shaft 276 to cause the lever 284 to pivot, while the solenoid 302, through the lever 306, effects displacement of the rack 296 and swing-

ing of the lever 290 which displaces the pilot stem 316 and thereby admits pressurized fluid behind the actuator 332 so that on outward movement of the actuator 332 against the lever 284, the latter will displace the valve stem 256 to its extreme right position as shown in Fig. 23. Note that Fig. 19 is a view from the opposite side, so that there the rapid approach position of the valve stem 256 is shown as the extreme left position.

As the ram drill head 22 moves forward on initiation of drilling, the projecting arm 366 of the latch dog 362 contracts the projection 426 of the lever 420 and swings the latter whereby the rack 412 is displaced inwardly and the pinion 410, and thereby also the shaft 404, are rotated to bring the latter into the position where the two pins 434 and 442 are aligned and the feed set dog 406 assumes a vertical position.

Whichever way drilling was initiated, the lever 280 was swung over to the left, and, as a result, its projection 282 no longer extends horizontally but rather upwardly and into the path of the slip dog 388. Hence, as the latter moves forwardly with the slip rod 386, the cam surface 398 of the slip dog 388 engages the projection 282 of the lever 280. The proportions and configurations of the projection 282 and the cam surface 398 are so balanced, and the pressure of the spring 392 in the slip dog 388 (which spring pressure controls resistance against slipping of the dog 388 on the slip rod 386) is so adjusted, that upon such contact of the cam surface 398 of the dog 388 with the projection 282, the lever 280 will be swung to the right, to bring the valve stem 256 into feed position, i.e., into central right position, and so that thereafter the dog 388 will be held against further movement by the projection 282. Then the rod 286 will slide through the dog 388 as the latter is held stationary. It will be understood that, before a drilling operation is initiated, the dog 388 is positioned on the slip rod 386 at a point selected so as to cause initiation of feeding movement of the ram drill head 22 after rapid approach over a predetermined distance.

When, as feeding progresses, resistance to feeding or to drill driving torque becomes excessive and, as a result, either the switch 102 is actuated by the torque responsive overload release safety clutch including the collar 98 or the switch 312 (which is arranged in parallel with the switch 102) is actuated by the safety overload relief valve 314 responsive to excessive fluid pressure, then the return solenoid 304 is energized and by the means above described shifts the lever 284 and thereby the valve stem 256 to rapid return position, i.e., extreme left position. On this returning movement, the slip dog 388 retains its position on the slip rod 386, which, of course, shares the return movement of the ram drill head 22.

At the end of the return stroke, the pin 442 carried by the arm 444 of the bracket 380 on the lateral extension 348 of the ram drill head 22 contacts the pin 434 carried by the inturned arm 438 extending from the sleeve 428 of the rock shaft 404, moves the pin 434 against the force of the spring 436 against the upstanding finger 300 of the rack 296 and thereby displaces the latter to turn the lever 290 to move the pilot stem 332 admitting pressurized fluid behind the actuator 316 so that the lever 284 again moves the valve stem 256 to rapid approach position (extreme right).

Next, the slip dog 388 again actuates the mechanism described above to initiate feeding movement of the ram drill head 22, but this time only after rapid approach has continued to the point where return movement was started. Note that the slip dog 388 was held by the lever projection 282 throughout the previous feeding stroke while the rod 286 was allowed to slide therethrough. Thus, the dog 388 has been displaced to the rearwardly or to the right on the rod 286 over a distance corresponding to the forward movement of the ram drill head 22 during the next preceding feeding stroke of the ram drill head.

In the manner indicated, a series of rapid approach, feed, and return movements are performed until a predetermined drilling depth has been reached. At that time, the ram drill head is returned to its starting position as follows. The pin 356 of the reset dog 352 contacts the projection 426 of the lever 420 to move the rack 412 and to rotate the pinion 410 whereby the rock shaft 404 is shifted to bring the pin 434 out of alignment with the pin 442 and to incline the lower end of the dog 406 inwardly. At almost the same time, the pin 356 of the reset dog 352 also contacts the upstanding arm 300 of the rack 296 whereby the valve stem 256 is brought to rapid return position (extreme left) as described above. It will thus be noted that by adjusting position of the reset dog 352 the drilling operation can be terminated at any predetermined depth. As the ram drill head 22 moves rearwardly in its rapid return, the inturned lower end of the feed set dog 406 contacts the slip dog 388 to hold the latter as the rod 386 slides therethrough. Since the pin 434 now is not interposed in the path of the pin 442, the upstanding finger 300 of the rack 296 is not contacted, the rack 296 is not moved, and the return movement is not terminated by another rapid approach stroke of the ram drill head 22. Instead, the rapid return movement is terminated by the piston 108 being held against further rearward movement by the cap 118 of the fluid motor 103. Thereafter, the control lever 280 is manually moved into the position corresponding to the neutral position of the valve 254.

If at any time during a drilling operation it is desired to interrupt the same before drilling is completed, the lever 430 may be swung to rock the shaft 404 into the position where the pin 434 is no longer aligned with the pin 442, either of the switches 102 or 312 may be actuated manually, and when the rapid return movement thus initiated has been terminated, the control lever 280 may be moved to neutral position. A new drilling operation may then be started.

Hydraulic system

The mechanical aspects of the movements of the ram drill head 22 having been described hereinabove along with the plunger pump 140, the hydraulic system of the machine of the present invention and its functioning will now be disclosed. This disclosure will include, first, a description of certain valves and other flow regulators forming part of this hydraulic system and, secondly, a description of the hydraulic system as a whole.

Reference is made to the diagrammatic representation of the main control valve 254 in Figures 22 to 25. As shown, that portion of the valve stem 256 slidable within the bore 260 in the housing 264 includes four enlarged portions 446, 448, 450 and 452 slidably fitting the bore 260 in the housing 264 and spaced by intermediate restricted stem portions 454, 456, and 458. Further, the bore 260 is provided with four circumferential grooves communicating, respectively, with fluid channels 460, 136, 464 and 466, 138 and 470. As will be discussed further hereinbelow, conduit 464 is connected to a source of pressurized hydraulic fluid; conduits 436 and 438 are connected to the fluid motor 103; conduits 460 and 470 are connected to a reservoir for hydraulic fluid; and conduit 466 is connected to the conduits 340 and 342 leading to the bores 328 and 330 of the pilot stems 332 and 334. The direction of flow, if any, of hydraulic fluid through the valve 254 in the various operative positions of the valve stem 256 is as follows. When the valve stem 256 is in rapid approach position (extreme right, as shown in Figure 23), fluid under pressure enters the valve 254 from conduit 464, flows along the reduced valve stem portion 456 and is discharged through conduit 138 for flow to the fluid motor 103. At the same time, fluid discharged from the fluid motor 103 enters the valve 254 through conduit 136, flows along the reduced valve stem portion 454 and is discharged through the conduit

460 for flow to the reservoir. When the valve stem 256 is in feed position (central right, as shown in Figure 24), all interconnecting passages within the valve are blocked, so that no flow can occur between the conduits 460, 136, 464, 138 and 470. The enlarged valve stem portions 448 and 450 block any flow from the inlet conduit 464 and also any flow into or out of the conduits 136 and 138. The drain conduits 460 and 470 are blocked and isolated by pairs of enlarged valve stem portions 446 and 448, on the one side, and 450 and 452 on the other side. Similarly, when the valve stem 256 is in neutral or stop position (central left, as shown in Figure 22), all interconnecting passages within the valve are blocked, so that no flow can occur between conduits 460, 136, 464, 138 and 470. When the valve stem 256 is in rapid return position (extreme left, as shown in Figure 25), pressurized fluid enters through conduit 464, flows along the restricted valve stem portion 456 and is discharged through conduit 136 to the fluid motor 103. Fluid draining from the fluid motor 103 enters the valve 254 through conduit 138, flows along the restricted valve stem portion 458 and is discharged through conduit 470 to the reservoir. However, at all times flow of pressurized fluid is possible from the conduit 464, around the reduced valve stem portion 456 and out through the conduit 466 to the pilot stem bores 328 and 330.

The above noted safety overload valve 314 is shown in detail in Figures 15, 16 and 18. The valve 314 extends along with a sequence valve generally indicated at 472 within one and the same housing 474 and these two valves have a common inlet port 476 receiving pressurized fluid from the conduit 234. The bore of the valve 314 extends at right angles to the port 476 and includes a first restricted portion 480 and a second expanded portion 482, a valve seat 484 being defined at the juncture of these two valve bore portions. The valve 314 further includes a stem 486 having a face urged against the valve seat 484 by a spring 488 seated in the enlarged bore portion 482. The valve stem portion within the restricted valve bore 480 is fluted to permit the hydraulic fluid to exert pressure against the valve face and to force the latter off the valve seat 384 if and when the hydraulic pressure is strong enough to compress the spring 488. In this event, the fluid flows into the expanded bore portion and is discharged through a central opening into a conduit 490. Further, the valve stem 486 is provided with an extension rod 492 projecting through a cap 494 outwardly from the housing 474 and capable, when the face of the valve stem 486 is displaced from the valve seat 484, of actuating the switch 312. The valve 314 functions as an overload or relief by-pass valve responsive to excessive hydraulic pressure and also actuating the switch 312 to initiate return of the ram drill head 22 from the work piece.

The sequence valve 472 includes a restricted bore portion 496 and an expanded bore portion 498, a valve seat 500 being defined at the junction of these two bore portions. A fluted valve stem 502 is turned with a face urged against the seat 500 by a spring 504. When the valve face is displaced from the seat 502, flow of hydraulic fluid into the expanded bore portion 498 takes place, and the fluid is discharged through a lateral aperture into a conduit 506 which in turn discharges into the conduit 138, as explained hereinbelow. The function of the sequence valve 472 is to determine (by the setting of the spring 504) a minimum pressure for flow of hydraulic fluid therethrough.

The valve housing 474 also includes a channel 508 having therein a screw plug 510 formed with a restricted orifice 512 therethrough. Fluid enters the channel 508 from a conduit 514 (which is a branch of the conduit 464, as explained hereinbelow) and is discharged into a conduit 516. The function of this structure is disclosed hereinbelow.

The valve housing 474 also accommodates a strainer 518 in an appropriate recess 520. Fluid flows into the

recess 520 from a conduit 522 into and through the strainer and is discharged through the conduit 192.

Referring now to Figures 1 and 14, the hydraulic system of the present invention further includes a charge control valve disposed within a housing 525. This valve is generally indicated at 526 and comprises a valve body 528 having a bore 530 fitted with a stem 532. The bore 530 is connected by appropriate parts with an inlet conduit 534 (which is a branch of the conduit 516, as explained hereinbelow), with the conduit 522 (which functions as an outlet conduit) and with a drain conduit 538. A spring 540 urges the valve stem to the left (as shown in Figure 14). The valve stem 532 includes a restricted portion 542 and disk shaped enlarged end portion 544 on the right side extending in a circumferential groove 546 in the bore 530. This disk 544 blocks flow of fluid through the bore 530 when the stem 532 is displaced to the left by the spring 540. The valve 526 is operated by a solenoid 548 having a finger 550 which, when the solenoid is energized, pivots to move the valve stem 532 to the right, permitting fluid from the conduit 534 to flow around the restricted valve stem portion and out of the valve through the conduit 522, access to the drain conduit 538 being blocked by the disk 544. The bore 530 is closed by a cap 552 which also carries the fixed end of the spring 540. The function of the charge control valve 526 will be discussed hereinbelow.

The solenoid 548 is operated by a switch 554 shown in Figures 1 and 6 which in turn is actuated by a finger 556 carrying at its end a roller 558. As shown, the switch 554 is mounted on the drill head carrier 16 and the roller contacts one side of the ram drill head 22, being lifted to actuate the switch 554 by a cam 560 on the ram drill head 22 located so that on rapid approach of the ram drill head the switch 554 will be actuated before the ram drill head 22 begins feeding movement. On rapid return of the ram drill head, the switch 554 is again actuated, the finger 556 being urged against the ram drill head 22 by a spring (not shown).

The hydraulic system as a whole will now be described, reference being made to the purely diagrammatic representation in Figure 26. As shown, this hydraulic system includes a tank or reservoir 562 for hydraulic fluid which is withdrawn therefrom through a conduit 564 by a pump 566 for pressurizing and subsequent discharge through a conduit 568. The pump 566 is suitably a gear pump of the type shown in Figures 4 and 25 through 29 of my co-pending application Serial No. 437,067, filed on June 16, 1954, and entitled "Material Working Apparatus," although other gear pumps or the like may also be employed for pressurizing the hydraulic fluid ahead of the pump 140. The preloading gear or other pump puts the hydraulic fluid under considerable pressure and this materially increases the efficiency of the pump 140. This results from the fact that the fluid entering the pump 140 has been slightly compressed so that it cannot be further compressed an appreciable amount by the pump 140. While, of course, the amount by which unpressurized fluid might be compressed by the pump 140 is small (about 0.05%), such compression is often sufficient to introduce undesirable variation in the movement of the ram drill head 22. In addition, the preloading of the charging fluid substantially eliminates any possibility of fluid leaking back through the check valves of the pump 140 during pumping strokes of the pump pistons.

The pump 566 delivers the pressurized fluid through the conduit 568 to a relief valve 570 which acts to limit the maximum pressure delivered by the pump 566, excess fluid being directed back to the reservoir 562 through a conduit 572. The drain conduit 538 from the charge control valve 526 also discharges into this conduit 572. From the relief valve 570 the pressurized fluid flows through a conduit 574 to a pressure reducing valve 576. It should be understood that the reservoir 562, the pump 566, the valves 570 and 576 and the conduits 564, 568,

572 and 574 are not included in the machine shown in Figure 1, but are provided and mounted separately therefrom to function as a source of pressurized fluid for a plurality of machines of the type shown in Figure 1. In each such machine there is provided a pressure reducing valve (not shown) similar to valve 576 and connected to the relief valve 570 in parallel with the valve 576 by suitable conduits (not shown). These pressure reducing valves connected in parallel to the relief valve insure that each drilling machine will receive an adequate supply of fluid under sufficient pressure. Each drilling machine is provided with suitable drain conduits (not shown) which direct fluid back to the reservoir 562 similarly to the drain conduits of the machine of Figure 1, as disclosed hereinbelow. If only a single drilling machine is ever to be operated by pressurized fluid supplied from the pump 566, the valve 576 may be omitted.

From the pressure reducing valve 576, pressurized fluid flows through conduit 464 directly to the main control valve 254 for flow therethrough and through conduits 136 or 138 (when the valve 254 is in rapid approach or rapid return position) to the fluid motor 103. Note also that (when the valve 254 is in rapid approach or rapid return position) either the conduit 136 or 138 serves as a return conduit for the fluid motor 103 to the valve 254, the returned fluid being discharged either directly through the conduit 460 to a drain conduit 578 discharging into the reservoir 562 or indirectly through conduit 470 into the conduit 490 which in turn discharges into the conduit 578. Note further that pressurized fluid is always supplied from the conduit 464 through the main valve 254 to the conduit 466 having the two branch conduits 340 and 342 connected to the pilot stems 332 and 334 connected by the conduits 324 and 326 to the actuators 316 and 318. The drain conduits 344 and 346 from the pilot stems 332 and 334 discharge into the drain conduit 578. Thus, the pressurized fluid for effecting rapid approach and rapid return of the ram drill head is supplied directly from the pump 566 under the control of the main valve 254.

When the main valve 254 is in neutral position and the charge control valve 526 is closed, the solenoid 548 being deenergized, no hydraulic flow takes place in the machine. Flow of pressurized fluid from the conduit 464 through the valve 254 into the conduits 136 and 138 is blocked, and flow from the conduit 466 and its branches 344 through the pilot stem 332 is likewise blocked. Flow of pressurized fluid through the conduit 514 (which branches off from the conduit 464), through the restricted orifice 512, through the conduit 516 and through the conduit 534 (which is a branch of the conduit 516) and through the valve 526 is blocked due to the fact that the valve 526 is in closed position. A conduit 580 branching from the conduit 516 and communicating with the conduit 136 is likewise blocked, for no discharge into and through the closed valve 254 is possible, either directly from the conduit 136 or through the fluid motor 103 and thence through the conduit 138. Further, the conduit 506 is connected to the conduit 138, but flow from the conduit 138 and the conduit 506 through the valve 472 is impossible, the valve 472 being a one-way check valve.

It may be noted, in this connection, that when the valve 254 is in rapid approach position, a small amount of the pressurized fluid flows through the conduit 514, the restricted orifice 512, the conduit 516 and the conduit 580 into the conduit 136 where it rejoins the bulk of the fluid flowing to the main valve 254 through the conduit 136.

In the last stage of the rapid approach movement of the ram drill head 22, the switch 554 is actuated as its finger 556 is lifted by the cam 560 and the solenoid 548 is energized, whereby the charge control valve 526 is opened for flow of fluid from the conduit 534 into the

conduit 522, through the strainer 518, the conduit 192, the pump 140, the conduit 234, the sequence valve 472, the conduit 506 and the conduit 136 into the fluid motor 103.

When the valve 254 thereafter is moved into feed position, all intercommunication through the valve 254 between the conduits 460, 138, 464, 136 and 470 is blocked. The hydraulic circuit then is substantially closed. The feed pump 140 delivers pressurized fluid at a metered rate through conduit 234, sequence valve 472 and conduit 506, causing the fluid motor 103 to move the ram drill head 22 forward at a rate dependent only on the delivery of the pump 140. Forward movement of the piston 112 of the fluid motor 103 forces fluid from the cylinder 104 into the conduit 136 from where it flows into conduit 580 and through the valve 526, conduit 522, strainer 518 and conduit 192 back to pump 140, where the fluid is repressurized and again discharged through conduit 234, thus completing the closed circuit. An amount of fluid sufficient to make up for the extension of the piston rod 112 from the cylinder 104 on continued feeding movement is admitted to the low pressure side of the above noted closed feed circuit from conduit 514, orifice 512 and conduit 516, the orifice 512 functioning as a metering device and being effective to isolate the closed feed circuit from the pressurized fluid supplied from the pump 566. As noted hereinabove, the sequence valve 472 insures that no fluid will flow in the closed feed circuit unless sufficient pressure is developed by the pump 140 to effect proper feeding action and to eliminate any possibility that fluid would flow over the ball valves of the pump 140 into the feed circuit without being properly metered by the pump 140. As also pointed out hereinabove, the safety relief valve protects the feed circuit from undesirably high pressures, excess fluid being drained off through conduits 490 and 578 and the switch 312 being actuated to initiate rapid return of the ram drill head 22.

General function of the machine

The machine of the present invention is particularly adapted for uses such as drilling oil holes 584 in automobile crankshaft 582 shown in Figures 27, 28, 29 and 30. For this purpose a number of drilling machines such as the machine 10 of Figure 1 may be set up to drill simultaneously all the oil holes 584 in a single crankshaft 582, pressurized fluid being supplied to all the machines from a single gear pump 566, as shown in Figure 26. Before drilling is initiated, the drill head carrier 16 of each machine 10 is adjusted to a proper distance from the workpiece by a suitable displacement on the guideway 14. Further, the slip dog 388 of each machine 10 is adjusted on its slip rod 386 to initiate feeding movement of the ram drill head 22 just before the latter contacts the workpiece, and the reset dog 352 of each machine 10 is also adjusted to terminate the drilling cycle of each machine 10 when a hole of desired predetermined depth has been drilled.

When thereafter drilling is initiated, each machine 10 will complete its drilling cycle independently of the other machines. The ram drill head 22 of each machine 10 will be withdrawn from the workpiece whenever excessive torque or thrust resistance is encountered in drilling a particular oil hole 584, which will vary from machine to machine and as between the various holes being drilled, since all drills 40 are not equally sharp and do not wear down at the same rate, and since the material of the crankshaft 582 will exhibit local variations in hardness.

By way of a specific example, typical data illustrating the time required for drilling of oil holes in an automobile crankshaft are given as follows: The material of construction was A1S1-1045 forged steel; the drill size, $\frac{3}{16}$ inch diameter; the drill speed, 688 revolutions per minute and 45 surface feet per minute; the feed rate, 5.07 inches per minute and 0.0076 inch per drill revolution;

and the total drilling depth, $2\frac{1}{2}$ inches. The drilling required four separate drill entries into the workpiece. The elapsed time (in seconds) is tabulated as follows:

Entry:	Time
1	20.5
2	4.0
3	3.6
4	2.0
Total	30.1

Another example will illustrate the depths drilled before occurrence of overload and withdrawal of the ram drill head 22 from the workpiece. The conditions of drilling were similar to those described in the preceding paragraph. The data are tabulated as follows:

Test Number	Inches of Drill Depth At Overload Tripping						Total Drilled Depth
	Entry #1	Entry #2	Entry #3	Entry #4	Entry #5	Entry #6	
1	2.64	.97	.76	.51			4.88
2	2.60	.51	.45	.44			4.00
3	2.53	.79	.55				3.87
4	2.50	.55	.54	.41			4.00
5	2.06	1.03	.49	.38	.36	.18	4.50
6	1.70	.33	.30	.17			2.50

The above described specific examples or tests are merely illustrative. Many details of the above disclosed specific machine may be varied without departing from the principles of this invention. It is therefore not my intention to limit the scope of this application otherwise than necessitated by the scope of the appended claims.

The invention is hereby claimed as follows:

1. In a metal working machine comprising rotatably drivable tool spindle means, an electric motor for rotating said spindle means, a fluid motor for actuating said spindle means longitudinally for feeding a cutting tool into said work piece and for returning said spindle means, positive displacement variable delivery hydraulic pump means in alignment with said spindle means, said pump means including a drive shaft which is a portion of said spindle means for actuating said spindle means longitudinally at a feeding rate controlled positively and directly in accordance with the rate of rotation of said spindle means, and means responsive to a predetermined torque experienced by said spindle means during the feeding thereof to initiate return of said spindle means.

2. A metal working machine comprising rotatable rigid tool spindle means, an electric motor for rotating said spindle means, a fluid motor for actuating said spindle means longitudinally for rapid approach toward a work piece, for feeding a cutting tool into said work piece, and for returning said spindle means, means for supplying fluid to said fluid motor to effect selectively rapid approach and return of said spindle means, positive displacement variable delivery hydraulic pump means in alignment and having a drive shaft provided by a portion of said spindle means for actuating said spindle longitudinally at a feeding rate positively and directly controlled in accordance with the rate of rotation of the spindle

means, and resilient means responsive to a predetermined torque experienced by said spindle means during the feeding thereof to initiate return of said spindle means.

3. A metal working machine comprising a spindle including rotatably supported tubular means and an elongated rigid member for supporting a tool axially slidably and rigidly non-rotatably supported in said means, a fluid motor for actuating said elongated member longitudinally for rapid approach toward a workpiece, for feeding a cutting tool into a workpiece, and for returning said member from a workpiece, means for supplying fluid to said fluid motor to effect selectively rapid approach and return of said member, positive displacement variable delivery hydraulic pump means on said rotatable tubular means and including a drive shaft which is a portion of said rotatable tubular means and connected with said fluid motor for actuating said elongated member longitudinally at a feeding rate positively and directly controlled in accordance with the rate of rotation of said elongated member.

4. An apparatus, as defined in claim 3, including a drive mechanism for rotating said tubular means said drive mechanism comprising a rotary driven member freely disposed on said rotatable tubular means, and means resiliently engageable with said driven member for driving said tubular means and responsive to a predetermined torque experienced by said rotatable tubular means during a workpiece machining operation to initiate return of said elongated tool supporting member.

5. An apparatus, according to claim 3, wherein said elongated member comprises a first elongated splined portion disposed within said tubular means, and a second elongated portion projecting axially outwardly of said tubular means, said fluid motor including an elongated hydraulic cylinder disposed adjacent and parallel to said second elongated portion, a piston slidably disposed within said cylinder, an elongated rod having one end connected with said piston and an outer end projecting from said cylinder, and slide means secured to the outer end of said rod and rotatably receiving and supporting said second portion of the elongated member, said slide means including means retaining said elongated member for axial movement with the slide means.

6. In a metal working machine comprising rotatably drivable tool spindle means, a fluid motor for actuating said spindle means longitudinally for feeding a cutting tool into a workpiece and for returning the spindle means, and positive displacement variable delivery hydraulic pump means in alignment with said spindle means and including a drive shaft which is a portion of said spindle means for actuating the spindle means longitudinally at a feeding rate positively and directly controlled in accordance with the rate of rotation.
